UNITED STATES PATENT OFFICE.

EDWARD KENER, JR., OF BUFFALO, NEW YORK.

COMBINATION GAS AND SOLID FUEL RANGE.

1,179,529.

Specification of Letters Patent. Patented Apr. 18, 1916.

Application filed January 10, 1913. Serial No. 741,233.

To all whom it may concern:

Be it known that I, EDWARD KENER, Jr., a citizen of the United States, residing at Buffalo, in the county of Erie and State of New York, have invented new and useful Improvements in Combination Gas and Solid Fuel Ranges, of which the following is a specification.

This invention relates more particularly to a stove or range designed for burning either solid or gaseous fuel according to whichever is more convenient or available.

It is the object of this invention to provide a range of this character which can be produced at comparatively low cost, which has a grate for burning hard fuel and a burner for gaseous fuel, which can be readily converted for utilizing one or the other form of these fuels, and which gas burner can be readily and quickly placed in its operative position within the range and removed therefrom and also quickly adjusted for adapting the gas burners for burning either natural or artificial gas.

In the accompanying drawings consisting of 3 sheets: Figure 1 is a vertical longitudinal section of a combination gas and solid fuel range embodying my improvements. Figs. 2 and 3 are vertical transverse sections on the correspondingly numbered lines in Fig. 1. Figs. 4 and 5 are horizontal sections taken on the correspondingly numbered lines in Figs. 2 and 3. Fig. 6 is a fragmentary vertical longitudinal section of the stove, on an enlarged scale, taken on line 6—6, Fig. 2 and showing the improved adjustable damper. Fig. 7 is a vertical transverse section on line 7—7, Fig. 6. Fig. 8 is a fragmentary vertical transverse section taken on line 8—8, Fig. 4 and showing the improved means for removably and adjustably mounting the gas burner in the range. Figs. 9 and 10 are fragmentary vertical longitudinal sections taken on the correspondingly numbered lines in Fig. 8 looking in the direction of the arrows associated with these lines.

Similar characters of reference indicate corresponding parts throughout the several views.

1 represents the fire box or pot of the range or stove, 2 the grate at the lower end of the fire box and 3 the ash pit arranged below the grate all of which parts may be of any suitable and well known construction. As shown in the drawings, the rear

transverse wall or side 4 of the fire box is lined with fire brick and its front transverse side 5 is constructed in the form of a hollow water chamber through which water is circulated and heated by the fire in the pot or box in a well known manner. In front of the water chamber is arranged the breast 6 of the stove which is separated from the water chamber by an intervening air chamber or passage 7 and provided with air inlet openings 8 which are adapted to be controlled by dampers or slides 9. The air entering through these openings passes into the air passage 7 and thence downwardly in the same into the ash pit and thence upwardly past the grate to the solid fuel in the fire box for aiding in the combustion of the solid fuel. By separating the breast of the stove from the water box so as to form an intervening air passage between the same the heat of the fire box is prevented from warping this part of the stove and the air passing downwardly between the breast and the water chamber is heated preliminary to mixing with the solid fuel, thereby putting the same in the best condition for promoting combustion and economizing in the consumption of fuel.

10 indicates the oven which is preferably arranged in the rear part of the stove and above a line extending horizontally over the top of the fire box.

11, 12, 13, 14 indicate the horizontal main flue, the horizontal top flue, and the front and rear vertical transverse flues, respectively, whereby the heat from the fire box or other heating device is conducted around the bottom, top and transverse front and rear sides of the oven. The main flue 11 communicates at its front end with the top of the fire box and extends with its rear part underneath the lower side or bottom of the oven, the upper or top flue 12 extends horizontally over the top of the oven, the front transverse flue 13 is arranged transversely in front of the oven and connects the front end of the top flue with the main flue at a point about midway of the length of the latter and in rear of the fire box or other heating device, and the rear transverse flue 14 is arranged along the rear transverse side of the oven and communicates at its upper and lower ends with the rear ends of the top and main flues respectively, as shown in Fig. 1. The height of the front part of the main flue is greater

than the rear part thereof, this front part extending nearly to the lower end of the front vertical flue 13 and some distance beyond the rear side of the fire box. The bottom of the main flue is constructed to gradually rise from the fire box to the lower end of the rear vertical flue, as shown in Fig. 1. By this means the heat developed in the fire box or other heating device is caused to rise gradually or by successive steps and follow its natural tendency to go upward without interference, thereby promoting the draft through the stove and increasing the heating efficiency of the same.

15 15 represents a smoke box arranged behind the rear longitudinal side of the oven and the upper horizontal and front vertical flues. The upper part of this smoke box communicates with the central rear part of the top flue 12 by means of a passageway 16 and the rear end of the front vertical flue 13 communicates with the smoke box by means of a passageway 17. In its top the smoke box is provided with an outlet or damper opening 18 the upper end of which is surrounded by a smoke pipe collar 19 which connects with the lower end of a smoke pipe 20 whereby the products of combustion of the range or stove are carried off to the chimney.

30 At the lower end of the front vertical flue 13 is arranged a by-pass damper or valve 21 which is adapted to open or close the by-pass 22 between the lower end of the front flue and the central part of the main flue this damper being preferably pivoted at its front end adjacent to the front wall of this flue and adapted to be either raised into its inoperative vertical position for opening the passage, as shown by dotted lines in Fig.

35 40 1 or turned into a horizontal position for closing the passage 22, as indicated by full lines in this figure. This valve is shifted for this purpose by means of a horizontal transverse rod 23 connected with this damper 45 or valve and provided at its front end with a handle 24 for manipulating the same.

Within the upper flue 12 is arranged an upper baffle 25 which preferably extends from the rear longitudinal wall of this flue 50 adjacent to the rear edge of the rear passage 16 forwardly and inwardly to a point approximately in the center of this flue. Within the upper front flue 13 is also arranged a baffle 26 which extends from the rear longitudinal wall thereof at a point adjacent to the upper end of the passageway 17 inwardly and downwardly to a point approximately in the center of this flue.

60 65 When starting a new fire in the fire box or replenishing the same with fresh fuel the by-pass damper is opened so as to provide a direct communication between the fire pot and the smoke pipe at which time the heat and products of combustion pass from the top of the fire box rearwardly through the

high part of the main flue, thence into the adjacent shallow rear part of this flue and thence the bulk of this heat and the products of combustion escape through the passageway 22 into the upright front flue 13 and pass from thence through the passageway 17 in the rear longitudinal wall thereof into the smoke box and then out through the smoke pipe to the chimney. After the fire has been started and burns sufficiently bright the by-pass damper 21 is closed so that direct communication between the fire box and the smoke pipe is cut off and thereafter the heat and products of combustion are all compelled to pass rearwardly underneath the bottom of the oven, thence upwardly through the rear flue 14 along the rear transverse wall of the oven, thence forwardly through the top flue 12 and over the top of the oven until they reach the central part of this last mentioned flue at which place the upper baffle deflects the heat and gases toward the front longitudinal wall of this passage and part of the heat and gases pass around the front edge of this baffle directly backward through the passageway 16 into the smoke box and out through the smoke pipe, while another part of the heat and gases continue their forward movement in the top flue and pass downwardly in the front flue 13 and around the lower edge of the front baffle, thence laterally rearward through the passageway 17 into the smoke box and out through the smoke pipe. It will be observed that by this means the top and bottom and the front and rear transverse walls of the oven are all subjected to the heating effect of the heat and gases generated by the fire, thereby heating the interior of the oven uniformly in all parts thereof and enabling the articles placed therein to be cooked quickly, thoroughly and uniformly. By providing the baffles in the upper and front transverse flues the heat is prevented from passing directly out through the passageways 16 and 17 but is compelled to spread itself over substantially the entire area of the top and front transverse wall of the oven before it can escape, thereby obtaining the maximum cooking effect of this heat.

55 60 65 The top 280 of the upper flue 12 above the oven 10 serves as an elevated heating surface upon which vessels may be placed for cooking the contents thereof in addition to the vessels placed for this purpose on the depressed heating surface of the lower stove top 28, thereby furnishing a greater heating area for a given floor space compared with stoves as heretofore constructed. The elevated heating surface may be provided with openings which are normally closed by lids 281, as shown in Fig. 1.

65 70 75 When it is desired to utilize gas or similar fuel as the heating medium in place of

coal or similar solid fuel the range or stove is provided with the following means for this purpose: 27, 27 represent two individual front gas burners which are arranged respectively in the main flue underneath the front openings in the stove top 28 which are normally closed by the lids 29, and 30 represents an elongated multiple burner which is arranged in the high part 5 of the main flue underneath both of the rear openings of the stove top which are normally closed by the rear lids 31, 31. Each of these burners is connected with a branch gas pipe 32 which extends horizontally 10 through a vertical slot or opening 33 in the front longitudinal wall 34 of the main flue and is connected externally of the stove with a horizontal longitudinal gas supply pipe 35. The flow of gas from the supply 15 pipe to the branch pipe is controlled by a valve or stop cock 36 and air is mixed with the gas as it enters the branch pipe by means of an air mixer 37 in the usual and well known manner. When natural gas 20 is employed as the fuel, the burners are arranged a greater distance below the top of the stove than when burning artificial gas in order to compensate for the greater pressure at which natural gas is usually 25 supplied and also enable the natural gas to mix with the greater volume of air and thus produce complete combustion of the gaseous fuel as well as avoiding any odors of unconsumed gas and obtain the greatest advantage from the fuel. When burning natural gas the burners are lowered and the branch pipes thereof are moved into the lower parts of the slots 33 and when burning artificial gas the burners are raised and 30 their branch pipes are shifted into the upper parts of said slots. In order to permit of placing the branch pipes into either ends of these slots and covering up the unoccupied parts of the same so that air is prevented from passing through the same into the main flue, a shutter 38 is provided 35 which is preferably constructed in the form of a plate. The latter is adapted to engage removably with a seat 39 which is formed on the front longitudinal wall 34 of the main flue by means of pairs of upper and lower lugs and provided on one side of a horizontal longitudinal central line midway between the upper and lower edges of this plate 40 with a plurality of openings 40 each of which is adapted to receive one of the branch burner pipes. When the branch pipes are in their lowered position while burning natural gas the shutter plate is engaged with its seat 39 so that its openings 40 are below the center of this plate as indicated by full lines in Figs. 8 and 9 at which time the upper part of this plate covers the upper ends of the slots 33. When 45 the branch pipes are shifted into the upper parts of the slots 33 for bringing the burners nearer to the top of the stove while burning artificial gas the shutter plate is reversed in its seat on the stove so that its openings 40 are above the center of this 70 plate and in a position to receive the elevated branch pipes while the lower part of this plate covers the lower ends of the slots which at this time are unoccupied by the branch pipes. In this manner the 75 same plate can be utilized for closing the unoccupied parts of the slots 40 either when the burners are in a position for utilizing natural gas or artificial gas. 80

At the same time that the burners are shifted from the upper to the lower ends of the slot 40 or vice versa the extreme outer ends of these branch pipes are also shifted from the upper to the lower ends of the slots 41 or vice versa formed in a bracket 85 42 secured to the adjacent part of the stove top. The upper and lower ends of each of these bracket slots are enlarged to receive a branch pipe and the central part of each of these slots is constricted as shown at 42, so that when a branch pipe is in engagement with the upper end of a bracket slot it is prevented from moving downwardly to the lower end of this slot and when the branch pipe is in the lower end of this slot 90 the same is held against movement into the upper end of this slot. It will be obvious that by this means the branch pipes must be wholly withdrawn from the shutter plate and the bracket and then reinserted into the same in the changed position. The shutter plate is secured in place against the front wall of the main flue by means of screws 43 as shown in Fig. 9 or otherwise. 95

When the burners are not in use the same may be readily disconnected from the supply pipe inasmuch as the branch pipes are connected with the air mixers by means of slip joints. In order to render the burners readily accessible when required for use the same are preferably stored in a compartment 44 arranged underneath the rear shallow part of the main flue 11 which compartment is provided with an opening which is normally closed by a door 45. When the burners and their supply pipes are thus removed from the main flue and the heat for cooking purposes is produced by means of coal or wood fire the slots 40 are covered by means of a shutter 46 which is preferably pivoted to the inner side of the front wall of the main flue so that they can be swung over these slots and prevent the admission of air over the bed of fuel which otherwise would have the effect of cooling the fire and interfering with its efficiency. 100

When burning gas the course of the heat is along the underside, rear transverse wall, horizontal top, and transverse front wall of 115 the oven in the same manner as when the 120 125 130

heat is produced by a solid fuel fire. When burning gas, however, some of the heat may be admitted directly into the oven for the purpose of expediting the cooking of the food therein and for this purpose the bottom or underside of the oven is provided with an opening or passage 47 which is normally closed by a lid 48 when the solid fuel fire is used but which is uncovered when a gaseous fuel is employed. In order to permit this gas heat to operate most effectively on the food to be cooked the vessels containing the food are preferably supported upon an open work shelf or rack 49 which is supported within the oven at a distance above the bottom thereof and provided with a plurality of openings or slots through which the heat of the gas may pass upwardly in the oven and around the vessels containing the food. For the purpose of distributing the heat uniformly throughout the oven and preventing a concentration of the heat against the underside of the vessel, a baffle 50 is provided consisting preferably of a horizontal plate which is supported from the underside of the rack by means of hangers 51 and extends over the heat inlet passage 47 but terminates at its edges short of the vertical walls of the oven, as shown in Figs. 1 and 3. By this means the heat upon passing from the main flue upwardly through the passage into the lower part of the oven is spread by the oven plate 47 and then rises on all sides of the cooking vessel and also passes along the underside of the same as well as over the top thereof, thereby heating all of its parts equally and cooking its contents uniformly.

When gas heat is thus admitted to the lower end of the oven the products of combustion are permitted to escape from the top of the oven, this being preferably effected by means of a damper, valve or gate 52 which is constructed in the form of a plate sliding horizontally and lengthwise in a way 53 on the upper side of the oven top adjacent to the front longitudinal wall thereof and provided with a plurality of openings 54 which are arranged in a longitudinal row and adapted to be moved into and out of register with a longitudinal row of openings 55 in the adjacent part of the top of the oven. Upon shifting the valve plate 52 so that its openings are in register with the openings of the oven top the interior of the oven communicates with the upper flue and the cooking odors and gaseous fumes are free to pass from the oven into this flue for thoroughly ventilating the oven while burning gas. Upon shifting the slide valve 52 so that its openings are out of register with those of the oven top communication between the oven and the upper flue is cut off this being the position of the parts while burning solid fuel. The shift-

ing of the slide valve 52 is preferably effected by means of a rod 55 secured to the front end thereof and extending through the front transverse wall of the upper flue, as shown in Fig. 4.

For the purpose of permitting of broiling meat in the oven a gas burner 56 is arranged in the upper part of the oven and supplied with gas through a branch pipe 57 leading through the adjacent walls of the stove. This burner is preferably constructed to direct its flame downwardly against the material supported upon the grate or otherwise and while this burner is in use the ventilating slide valve 52 is opened so as to permit the odors and gaseous fumes to escape to the chimney.

When gas is used as the fuel the following means are provided for heating water for domestic use: 58 represents a heating chamber which is arranged in the corner between the rear transverse wall of the fire box and the underside of the main heating flue and has front and rear longitudinal walls 59, 60, a transverse wall 61, and an inclined bottom 62, the top being formed by the adjacent lower side of the main flue and the front transverse wall being formed by the adjacent part of the rear transverse wall of the fire box. All of the parts of this heating chamber just enumerated are normally fixed but the bottom is preferably movably supported so as to render the interior of this chamber accessible. For this purpose the lower front end of the inclined bottom is pivoted on the companion front transverse wall by means of hinges 63 so as to permit this bottom to swing vertically and a catch or turn button 64 is provided for connecting the rear upper edge of the bottom with the lower edge of the rear transverse wall when this bottom is in its operative or raised position. Within the upper part of this heating chamber is arranged a water conducting pipe or coil 65 and below this coil is arranged a gas burner 66 the flame of which is directed upwardly against the water coil and causes the water therein to be heated. This burner receives its gas supply from the main pipe 35 and is provided with a regulating valve or stop cock 67 and an air mixer 68 of the usual and well known construction. Air for supporting combustion in the heating chamber is supplied through openings 69 in the low part of the pivoted bottom and the products of combustion may escape through openings 70 in the rear longitudinal wall of this chamber. If desired, however, the heat of the burner in the heating chamber may be conducted into the main flue and utilized for assisting in heating or warming the oven by removing a lid 71 which covers an opening in the partition between the heating chamber and the high part of the main flue.

For convenience in lighting the water heating burner without opening the bottom of the same an igniting device is provided which is preferably constructed as follows: 5 72 represents an inverted lighting channel or hood arranged lengthwise in the heating chamber and having its front part extending over the central part of the burner therein while its rear end extends to the exterior of 10 this chamber. Upon turning on the gas to the water heating burner a part of this gas is conducted by the lighting channel 72 to the outer end thereof where it can be lighted by a match or taper and as the ignited gas 15 flashes back it ignites the gas issuing from the remaining openings thereof. At the outer end of the lighting channel the bottom is provided with an opening through which this end of the channel projects, the lower 20 part 73 of this opening being made of semi-tubular or cylindrical form so that when the bottom 62 is in its normal raised position this semi-tubular part is arranged immediately below the outer end of the lighting 25 channel and forms a complete cylindrical or tubular conduit therewith through which the gas issues for convenience in lighting the same.

Although the escape of the smoke or other 30 products of combustion from the smoke box through the outlet 18 and into the smoke pipe may be regulated or controlled in any suitable manner it is preferable to employ the means which are shown in the drawings 35 and which are constructed as follows: 74 represents a damper arranged within the collar 19 above the outlet opening 18 and mounted so as to be rotatable about a horizontal axis so that this damper can either 40 be arranged in a horizontal position in which it obstructs the outlet to the maximum extent, as indicated by full lines in Fig. 7, or the damper may be turned from a horizontal position into a more or less vertical 45 position for clearing the outlet and permit the escape of the products of combustion from the smoke box into the smoke pipe.

At one end the damper is provided with a trunnion 75 which is journaled in a bearing 50 76 formed on the stove top at one end of the outlet and damper opening and at its opposite end the damper is provided with a damper rod 77 arranged in line with its trunnion and extending through a notch or opening 55 78 in the lower edge of the adjacent part of the stove pipe collar. At its outer end this damper rod is provided with a crank 79 whereby the damper may be turned for regulating the area of the outlet through which 60 the products of combustion escape. At its free end this crank is provided with an off-set or laterally projecting handle or finger-piece 80 whereby the crank may be manipulated. Upon turning the crank until its 65 straight or even side opposite to its finger-

piece engages with the stove top the damper will be shifted into its horizontal or maximum closed position, as shown in full lines in Figs. 3, 6 and 7, while upon turning the crank in the opposite direction so that its 70 off-set handle or fingerpiece engages with the top of the stove, as indicated by dotted lines in Fig. 7, the damper will be arrested in a position in which it inclines and the smoke outlet is uncovered accordingly. By 75 this means the attendant by simply swinging the handle or crank of the damper into either one or the other of its extreme positions will know definitely that the damper is either closed to its maximum extent or is 80 open partly suitable for producing a proper draft through the stove or range, thereby avoiding the necessity of any calculation for this purpose. If desired, the crank may be turned so that it projects upwardly from 85 the damper rod in which position the damper would stand vertical and provide the maximum opening in the smoke outlet.

In order to hold the damper reliably in its adjusted position without involving the 90 use of any intricate and expensive means for this purpose, a retaining device is provided which comprises a locking collar 81 arranged on the damper rod within the stove pipe collar and provided on its periphery with a plurality of flat facets 82 which are adapted to engage with a socket 83 arranged in the adjacent part of the stove top and having a plurality of angular facets 84 corresponding to those of the locking 95 collar. Although the number of facets on the locking collar and the locking socket may be varied it is preferable to provide the locking collar with eight of such facets so that the same is of octagonal form and the 100 socket is provided with three facets which correspond to those of the locking collar. Upon turning the damper by means of the damper rod and handle the locking collar by turning in the socket raises the adjacent 105 end of the damper slightly owing to the cam action of the peripheral form of the collar until the facets of the latter again correspond to those of the socket when the respective end of the damper again drops. 110 Owing to this angular formation of the co-operating surfaces of the locking collar and the socket the weight of the damper is utilized to hold the same yieldingly in the various adjusted positions which it is capable of 115 assuming within the range of movement of the crank, these various positions being determined by the number of co-operating facets on the locking head and socket. This means of holding the damper yieldingly in one position or another is exceedingly simple and inexpensive, it is not liable to get out of order and effectually holds the damper in the various positions required.

This combination gas and solid fuel stove 120

or range can be very readily converted for use either as a gas range or as a solid fuel range and works effectively with either of these fuels, thereby rendering the same particularly useful in territories where gaseous fuel is liable to become temporarily exhausted and necessitates utilizing coal or wood as the fuel for a brief time.

I claim as my invention:

- 10 In a stove or range, the combination of a heating device, an oven, a main flue extending horizontally from said heating device along the underside of said oven, a smoke box arranged along the rear longitudinal side of the oven and having an outlet at its top, a rear vertical transverse flue arranged along the rear transverse side of the oven, an upper horizontal flue arranged above the oven and communicating with the upper end 15 of said rear transverse flue and also connected by a passageway with the upper part 20

of said smoke box, a vertical transverse front flue arranged along the vertical front transverse side of the oven and communicating at its upper end with said upper horizontal flue and connected between its upper and lower ends by a passageway with said smoke box and connected at its lower end by a by-pass with said main flue, a by-pass damper for controlling said by-pass, a baffle arranged in said front vertical flue between its passageway leading to the smoke box and the upper horizontal flue and a baffle arranged in said upper horizontal flue between said rear transverse flue and the passage connecting the latter with said smoke box.

Witness my hand this 7th day of January, 1913.

EDWARD KENER, JR.
